STOCK FEEDING MECHANISM

James L. Giffen, Hudson, N. Y., assignor, by
mesne assignments, to Emhart Manufacturing
Company, a corporation of Delaware

Application June 11, 1946, Serial No. 676,041

6 Claims. (Cl. 271—2.5)

1

This invention relates to stock feeding mechanism and has for its general object and purpose to provide certain important improvements in my prior invention disclosed in United States Patent No. 2,330,119, issued September 21, 1943, whereby, in a materially simplified construction, increased operating efficiency, utility and reliable service of such mechanisms will be realized.

As shown in the above patent, the mechanism is adapted to intermittently feed the stock, usually supplied in strip form from a reel, to a punch press or other machine where the stock is operated upon by suitable tools. This mechanism is essentially characterized by opposed cooperating stock feeding members, one of which is associated with a friction braking unit and operated in timed relation to the punch press, whereby said member will first be moved into gripping engagement with the stock, and then actuated against the resistance of the braking unit to impart a rectilinear feeding movement to the stock.

It is one of the important objects of the present invention to provide an improved assembly and cooperative connection between the stock feeding member and the braking unit, whereby automatic compensation for brake lining wear is obtained with a more cohesive gripping pressure engagement of the feed member with the stock prior to the actuation of said member in stock feeding direction.

A more particular object of the invention resides in the provision of multiple friction braking units with the brake bands mounted for rocking movement about a common pivot axis and the brake drums and actuating means for the stock feeding member floatingly supported by the brake bands.

It is another object of the invention to provide conveniently adjustable means for regulating the clearance between the opposed cooperating feeding members in accordance with varying thicknesses of the stock, with additional means operable to quickly increase such clearance relation between the feeding members to facilitate the insertion or removal of the stock.

A further object of the invention is to provide simple and easily accessible means for adjusting the brake controlled stock feeding member to position its stock gripping surface out of parallelism with the surface of the opposed feeding member transversely of the path of feed and thereby compensate for inequalities in stock thickness.

An additional object of the invention is to provide stock-clamping means in advance of the

2

feeding members to prevent slipping or overrunning of the stock, with automatically operated means for releasing the clamping or holding pressure on the stock at the start of each feeding movement and restoring such clamping pressure at the end of the feeding movement.

It is also the aim and purpose of the present invention to provide a stock-feeding mechanism as above characterized in which the several co-operating elements are of rugged and durable structural form, which will reliably function to impart intermittent feeding movements of uniformly accurate length to the stock, and which will have a maximum period of useful service with negligible maintenance expense.

With the above and other subordinate objects in view, the invention comprises the improved stock feeding mechanism, and the construction and relative arrangement of its several parts, as will hereinafter be more fully described, illustrated in the accompanying drawings, and subsequently incorporated in the subjoined claims.

In the drawings wherein I have disclosed a simple and practical embodiment of the present invention, and wherein similar reference characters designate corresponding parts throughout the several views:

Figure 1 is a side elevation, illustrating one practical example of the present invention;

Figure 2 is a rear end elevation, certain parts being shown in section;

Figure 3 is a top plan view; and

Figure 4 is a transverse vertical sectional view taken substantially on the line 4—4 of Figure 1.

Referring in further detail to the drawings, in the selected embodiment of the invention, spaced parallel frame members 10 and 12 respectively are bolted or otherwise rigidly affixed to the bed of the punch press or other machine (not shown). Each of these frame members at its rear end is formed with a vertically extending portion 14, in the upper ends of which the opposite ends of a transverse rod or shaft 16 are securely fixed by means of the set screws 18.

As herein shown, two friction brake units are mounted upon the shaft 16 for rocking movement, each of these brake units including an adjustable brake band or strap embodying upper and lower sections 20 and 22 respectively, each of which

is internally faced with brake lining material 24. Each pair of brake-strap sections 20 and 22 are connected at their corresponding ends in a common hinge joint, indicated at 26 in Figure 3, and supported on the pivot rod or shaft 16 for unitary rocking movement about the axis thereof and for

relative pivotal movement. Relative axial movement of the brake-straps on the pivot rod 16 with respect to the frame members 10 and 12 is prevented by the rectangular spacing collar 28 on the rod 16 between said brake-straps.

Each pair of brake strap sections at their other ends are formed with apertured lugs 30 connected by the conventional bolt 32, brake spring 34 and adjusting nut 36 for adjustment of brake pressure in the usual manner. Within each of these adjustable brake straps a drum 38 is floatingly supported and a shaft 40 extends through the bearing hubs 42 of said brake drums. Between the drums, an operating or driving lever 44 is secured to shaft 40 by set screw 130, and each brake drum is rigidly secured to said lever by a plurality of bolts 46. A friction clutch connection is thus provided between arm 48 and the pivoted brake band members which carry arm 43. The lever 44 is provided with a horizontal arm 48 extending outwardly beyond the brake drums and having a forked terminal to which a coupling link 50 is pivotally connected as at 52. This link is adapted to be connected with the lower end of an actuating rod or pitman, the upper end of which is connected with a crank or eccentric at one end of the tool actuating shaft of the punch press or other machine as shown in Patent 2,330,119. At its inner end, lever 44 is formed with spaced legs 54 extending downwardly at the front and rear of the shaft 40. Between these legs, the upwardly extending rectangular shank 58 of a rockable stock gripping and feeding member 56 is received. This shank and the legs 54 of the operating lever are provided with coinciding apertures to receive the clamping bolt 60. One end of the bolt and the aperture in one leg 54 are threaded so that by adjustment of said bolt, the spaced legs 54 are drawn into tight clamping engagement against opposite sides of the rectangular shank 58, whereby the feeding member 56 is rigidly secured in fixed relation to lever 48 and brake drums 38. Set screws 62 threaded in the walls of the brake drums 38, bear against the other side faces of the shank 58 and by the adjustment of these screws, the feeding member 56 may be rocked about the axis of the clamping bolt 60 to position its stock gripping surface with respect to the path of feed of the stock. The member 56 is preferably of arcuate form and substantially concentric to the shaft 40.

In the rear ends of the frame members 10 and 12 and substantially in vertical alignment with the pivot rod 16, the opposite ends of the transverse shaft 64 are journaled. This shaft, at the inner side of each frame member, is formed with an eccentric portion 66, on which the parallel side arms 68 of a lever 70 are rockably mounted at their rear ends. These rear ends of the lever arms are integrally connected by the upwardly extending, inverted V-shaped leg 72 of the lever which is formed at its upper end with a boss 74 in which adjusting screw 76 is mounted. One end of this screw bears against the rear face of the spacing block 28 on rod 16 and the rear end of said screw carries a suitable lock nut 78.

In the lever arms 68, the opposite ends of a shaft 80 are securely fixed by means of set screws 82 and upon this shaft the lower cylindrical feed member 84 is supported for free rotation, said member being provided with suitable bushings 86 pressed into each end thereof to serve as bearings on the shaft 80.

Between the forward ends of the lever arms 75

68 a lower stock clamping member 88 is secured at its ends by the bolts 90. These forward ends of the lever arms are connected by the bar 92, having a bracket flange 94 at each end secured 5 to the respective lever arms by the screws 96. The bar 92 is provided with spaced longitudinally extending slots 98, in which the vertical bolts 100 carrying stock guiding rollers 102 are adjustably mounted. In advance of the feeding member 84, a stock supporting and guiding plate 104 is attached at its opposite ends to the upper edges of the lever arms 68 by screws 106. A similar stock guiding plate 108 extends between the lever arms at their rear ends, and is preferably 15 carried by a bracket member 110 detachably secured to a transverse connecting web 112 between the lever arms by means of screws 114.

Between the lower feeding member 84 and clamping member 88, each of the frame members 10 and 12 is formed with an upwardly extending lug 116. Upon a stud bolt 118 mounted in each lug 116, a lever 120 is fulcrumed intermediate of its ends. Between the forward ends of these levers and in vertically opposed relation to the lower clamping member 88, an upper clamping member 122 is secured by bolts 124. The rear ends of levers 120 are pivotally connected as at 126 to the lower end of arms 128, which are pivotally connected at their upper ends to the opposite ends of the brake drum carrying shaft 40.

It will be understood from the above description that by adjusting the screw 76 in the upper end of the lever 70, said lever may be rocked upon the eccentric portions 66 of shaft 64 to vary the clearance between the lower feed member 84 and clamping member 88 carried by said lever and the upper feeding member 56 and clamping member 122 respectively, in accordance with varying thicknesses of the stock. In order to quickly insert or remove the stock, I provide additional means for rapidly displacing the lower feeding and clamping members with respect to the upper cooperating members which comprises the lever 132 keyed to one end of shaft 64, as shown at 134, and fixed against axial movement on the shaft by set screw 136. This lever extends upwardly from the shaft and at its upper end carries the plunger or latch rod 138, axially movable through the hollow boss 140 on the lever and yieldingly urged in one direction by the spring 142 in said boss to engage the inner end thereof in the socket or bore 144 provided in a lug or boss 146 on the outer side of the adjacent part 14 of one of the frame members. The outer end of rod 138 is provided with a suitable hand knob 148 whereby said rod may be withdrawn from the recess 144.

With the lever 132 in its latched position as seen in Figure 1, lever 70 may be adjusted by means of screws 76 to regulate the stock feeding clearance between members 56 and 84. For the insertion or removal of the stock, the rod 138 is pulled outwardly and lever 132 is swung in the clockwise direction to a substantially horizontal position. Thus shaft 64 is rotated and the eccentric portions 66 on said shaft bodily displace the lever relative to the shaft axis rearwardly and downwardly, thus rapidly lowering the feeding member 84 and clamping member 88 so that the stock may be easily and quickly inserted between the feeding members or withdrawn.

Having now described the several structural features of the present invention, its operation will be understood as follows:

Having first properly adjusted the rollers 102

in accordance with the width of the stock, and with the lever 70 and members 84 and 88 in the downwardly displaced position as above explained, the stock S is inserted between clamping members 88 and 122 and feeding members 56 and 84 over guide plates 104 and 108 to a point rearwardly of said feeding members. After returning and securely latching the lever 70 in the position of Figure 1, it is then adjusted by means of screw 76 to establish a desired predetermined clearance relation between the feeding members 56 and 84 in accordance with stock thickness. In the downward movements of the driving connection, transmitted through lever arm 48, the stock will now be intermittently fed in timed relation to the operation of the punch press or other machine, and it will be noted that in the feeding portion of each operating cycle, owing to the frictional braking pressure of the brake straps upon the walls of drums 38, the entire assembly, including the brake units, operating lever 48 and rockable feeding member 56, is first swung downwardly about the axis of the rod or shaft 16 until such movement is stopped by the stock and the lower cylindrical feed member 84. Continued downward movement of lever arm 48 causes a frictional gripping pressure of the member 56 upon the stock until the frictional resistance of the brake bands to rotation of the drums 38 is overcome. This gripping pressure on the stock may thus be varied as required by the adjustment of the brake band springs 34. As the downward movement of lever arm 48 continues, the drums 38, with feeding member 56 rigidly connected therewith, are then rocked relative to the brake bands in an anti-clockwise direction to positively feed the stock S in the direction indicated by the arrow in Figure 1 of the drawings. Of course, it will be apparent that in the initial bodily movement of the brake units and lever assembly, the shaft 40 moves therewith, and through the connections 128 and 120, the upper clamping member 122 will be lifted out of contact with the stock so that the clamping members will offer no resistance to its feeding movement in the subsequent rocking motion of the feeding member 56. By proper adjustment of the driving connections, the downward movement of lever arm 48 may be varied to regulate the degree of rocking motion of feeding member 56 and the length of each rectilinear feeding movement of the stock S.

At the end of the feeding movement of member 56 and at the start of the upward movement of lever arm 48, the entire upper feeding assembly, including the two brake units, swings upwardly about the axis of pivot rod 16 and in this movement, levers 120 are rocked to force the clamping bar 122 downwardly and securely clamp and hold the stock between said bar and the lower clamping bar 88 on lever 76. Thus the slipping or overrunning of the stock beyond the pre-set length of feed is effectively prevented. The member 56 is thus lifted out of contact with the stock and as the drums 38 are rotated relative to the brake straps in the continued upward movement of lever arm 48 in the clockwise direction, the rocking movement of feeding member 56 is reversed and at the end of the upward movement of lever arm 48 the feeding member 56 is returned to its original position with respect to the feeding member 84 as seen in Figure 1 of the drawings.

It will be noted from the above description that the two brake drums and feeding member 56 are in effect journaled in the brake linings 24 so that the drums 38 will automatically center themselves

on the linings, regardless of unequal wear of the brake linings. Accordingly positive and effective gripping and feeding action of the member 56 is assured, even after prolonged periods of severe use. It will therefore be appreciated that by means of my present improvements, uniformity in length of the intermittent feeding movements of the stock is obtained with greater accuracy than has heretofore been possible. Also the greatly increased braking area and the means for adjusting and rigidly clamping the upper feeding member to the operating lever to compensate for inequalities in stock thickness, is an important feature of the present improvements.

15 It will further be seen that I have provided easily accessible means for quickly making the several required adjustments. It will also be noted that the several cooperating mechanical parts are of rugged and durable structural form and may be easily and accurately assembled for maximum operating efficiency. In view of the simplicity of my novel stock feeding mechanism, it will further be evident that the production cost thereof will be reasonably low.

20 The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

25 35 What is claimed and desired to be secured by United States Letters Patent is:

1. In strip feeding mechanism, opposed feeding and clamping members between which the strip passes, mechanism for moving one of said feeding members toward and away from the other during a strip feeding cycle, an adjustable support for the other feeding member and one of said clamp members, means for adjusting said support to variably regulate the strip feeding clearance between said members.

40 45 50 55 2. Strip feeding mechanism as defined in claim 1, comprising a rockably mounted shaft having an eccentric portion on which said support is rockably mounted, and a normally latched lever fixed to said shaft operable to rotate said shaft and angularly shift the position of said support relative to the shaft axis, whereby said members may be quickly separated independently of said adjusting means for insertion or removal of a strip between said members.

60 65 70 75 3. In an intermittent strip feed apparatus, a strip feed member having an arcuate strip engaging face, a supporting arm for said feed member mounted for rocking movement on an axis substantially parallel to the direction of feed of the strip, and an adjustable connection between said member and arm for rocking said feed member on said arm about an axis transversely of said first axis so as to properly position said strip engaging face relative to the strip.

4. Intermittent strip feeding apparatus comprising a pair of rockable feed members between which the strip is disposed during feeding, a spaced pair of strip clamping members, mechanism mounting one of said feed members for movement toward and away from the other feed member during strip feeding, a support for said other feed member and one of said clamping member, a fine adjustment for said support for setting a desired clearance between said pairs of

members, and a separate adjustment for said support for quickly displacing said one clamping member and said other feed member a substantial distance from the other clamping member and said one feed member for insertion or removal of said strip stock.

5. Intermittent strip feed mechanism comprising a frame, a member pivoted upon a fixed axis on said frame and swingable toward and away from the strip feed path, an arm pivoted on said member adapted to be connected to an actuator and carrying a strip feed element, a friction clutch connection between said arm and member permitting relative rotation of said arm and member when said feed element engages said strip, 15 synchronously operable strip clamping mechanism comprising a lever intermediately pivoted on said frame, a strip clamp on one end of said lever, and a link connecting the other end of said lever with said arm.

6. In strip stock feeding apparatus, a relatively stationary support, guide means for said stock on said support, and means for linearly feeding said stock through said guide means comprising a friction brake band assembly pivoted directly on 25 said support, a brake drum rockably and floatingly

supported within said brake band, a feed lever rigid with said brake drum and having a part adapted to be operably connected to a machine for performing an operation on said stock, a feed member having a section adapted to engage said stock, and a normally rigid adjustable connection between said lever and said member for properly positioning said section with respect to said stock.
